UNITED STATES PATENT OFFICE.

FREDERICK S. McCULLOUGH, OF WILKINSBURG, PENNSYLVANIA, ASSIGNOR TO WESTINGHOUSE ELECTRIC & MANUFACTURING COMPANY, A CORPORATION OF PENNSYLVANIA.

MULTIPLE-TRIODE VACUUM TUBE.

Application filed March 15, 1928. Serial No. 625,224.

My invention relates to thermionic devices or hot cathode devices, particularly to a novel arrangement of the electrodes of such devices.

5 Broadly speaking, the object of my invention is to provide a construction of thermionic devices or hot cathode devices which will permit the utilization of a plurality of anode elements with a single cathode in a single tube.

10 More specifically, the object of my invention is to construct a novel cathode for thermionic emission devices with which a plurality of anode structures may be employed, either for the purpose of passing a larger current through the device or for the purpose of utilizing a single device in place of a number of tubes such as triodes in the operation of a number of circuits.

15 In previous thermionic devices, the current which could be passed through the device at a given applied voltage, electron-emissivity and grid potential has been determined by the space-charge between the cathode and the anode, which, in turn, depends upon the distance between them. When attempts have been made to increase the current by placing the electrodes closer together, a limit has soon been reached because of structural difficulties.

20 Also, in previous devices only a single set of circuits has been usable with a given tube device, because of the fact that only a single anode structure or anode and grid structure could be employed.

25 In carrying my invention into effect, I attach to the cathode a plurality of radial plates or vanes which serve as shields dividing the electron stream into a plurality of separate segments. Each segment may then be provided with its own individual anode structure, or with an anode and control electrode structure. I prefer to utilize an indirectly heated cathode, such as is disclosed in the application of Freeman & Wade, Serial No. 611,263, filed Jan. 8, 1923, and assigned to the Westinghouse Electric and Manufacturing Company, because of the greater ease of attachment of radial plates to the indirectly heated cathode.

30 Other objects and constructional details of my invention will be apparent from the

following description and claims when read in connection with the accompanying drawings, wherein

55

Figure 1 is a perspective view of a thermionic device embodying my invention, parts being broken away, and

60

Figs. 2 and 3 are diagrammatic views of circuits utilizing my thermionic device.

65

In the drawings is shown a tube having a cathode 1 which is preferably composed of a cylinder which may be of nickel, platinum, tungsten or other suitable metal and is preferably oxide coated to increase the electron emission. The cathode 1, in the construction shown, is indirectly heated by a filament or heater element 2, which may be of tungsten, platinum, molybdenum or other suitable material, contained in an electrically insulating support which serves to conduct the heat from the filament 2 to the cathode cylinder 1. The support may be of zirconia or other suitable refractory material. The filament is provided with lead wires 4 which are sealed into a press 5 which also carries a supporting wire 6 for the cathode structure.

70

According to my present invention, I provide the cylindrical cathode 1 with a plurality of electrically conducting radial vanes or plates 7 which have relatively low electron emissivity and which may be secured to the cathode by welding, riveting, or other convenient means. As shown in the drawing, the plates 7 are shaped with ears at two adjacent corners to make attachment easy and also to allow contact between the vanes and the cathode only at the ends of the cathode cylinder 1, this being done to minimize heat conduction from the cathode to the vanes, thereby requiring less heating energy to maintain the necessary temperature in the cathode. In each of the spaces between the radial plates 7, is placed an anode 8 and grid 9 fulfilling the customary functions of such structures in standard triode tubes. The respective anodes 8 are supported by individual lead wires 11 sealed into the press 5 and the grids 9 are likewise supported by similar lead wires 12, also sealed into the press 5.

75

The operation of the device depends upon the fact that the vanes or shields constitute,

80

85

100

in effect, auxiliary control electrodes exerting a controlling effect upon the space-charge between anode and cathode. The space-charge is reduced by reason of the grounding of the vanes on the cathode, and hence the space current flowing under given conditions of cathode temperature and emissivity, electrode spacing and plate voltage is increased.

- 10 The vanes also divide the electron stream into independent portions which may be independently controlled, as shown in Fig. 3. Alternatively, all of the anode plate and grid structures may be connected together, 15 as shown in Fig. 2, either inside or outside of the tube, in which case the greater value of each individual electron stream in each sector as compared to the value of the electron stream in an equal sector without the 20 vanes or shields allows a substantially larger current to be passed through the tube, which results in a tube having not only a large current-carrying capacity but also a low impedance.
- 25 In the system illustrated in Fig. 3, the grid and anode plate structures are kept electrically separate and are connected to distinct sets of circuits, in which case the single tube will function in a manner similar to a group of tubes which have had their cathodes electrically connected, as is done in supplying a group of tubes from a single "A" battery, and their grid and anode plate structures connected in separate 30 sets of circuits, as is done in cascade amplification systems.

40 While I have shown only two systems and one tube structure in the accompanying drawing, it is obvious that my invention is susceptible of various changes and modifications without departing from the spirit and scope thereof. It is desired, therefore, that only such modifications and limitations be placed thereon as are set forth in the 45 prior art or in the appended claims.

I claim as my invention:

1. A vacuum tube having a single cathode, a plurality of anodes and means there-within for exerting a combined mechanical 50 and electrical action to substantially segregate the space discharges between the cathode and the respective anodes.
2. In a space-discharge device, a cathode, a plurality of anodes, a plurality of grids associated therewith, a single container therefor and means in said container for mechanically and electrically dividing the electrons emitted from said cathode into substantially separate streams associated 55 with the respective anodes and under the control of the respective grids.
3. The combination within a space-discharge device of a conducting element disposed in a radial position adjacent to the 60 flow path of the space discharge and means

for maintaining said element at such potential as to repel the main portion of the space discharge.

4. In a space-discharge device, the combination with an anode and a cathode, of 70 an auxiliary electrode positioned substantially convergent with the direction of flow of the space discharge between the anode and the cathode.

5. In a space-discharge device, the combination with an anode and a cathode, of 75 an auxiliary electrode positioned substantially convergent with the direction of flow of the space discharge between the anode and the cathode, and a conductive connection between said auxiliary electrode and said cathode.

6. In a space-discharge device, the combination with an anode and a cathode, of 80 and auxiliary electrode positioned substantially convergent with the direction of flow of the space discharge between the anode and the cathode, and a grid disposed transversely with respect to the flow of said space discharge.

90 7. A space-discharge device comprising two main electrodes, an auxiliary electrode positioned substantially convergent with the direction of flow of the space discharge between the anode and the cathode, and means for maintaining said auxiliary electrode at a predetermined potential with respect to one of said main electrodes.

8. A vacuum-tube device comprising a 100 cathode, means for exciting the same to an electron-emitting state, an anode, means for establishing a space, discharge flow between said anode, and said cathode, an auxiliary electrode positioned substantially convergent with the direction of flow of the space 105 discharge between the anode and the cathode, means for maintaining said auxiliary electrode at a substantially constant potential, a grid, an enclosing envelope for said cathode, anode, auxiliary electrode and grid, and a source of variable potentials for said 110 grid.

9. A space-discharge device comprising a substantially cylindrical cathode, a plurality 115 of segmental anodes disposed thereabout, and partition members for substantially segregating the space discharges between the cathode and the respective anodes.

10. A space-discharge device comprising a substantially cylindrical cathode, a plurality 120 of segmental anodes disposed thereabout, partition members for substantially segregating the space discharges between the cathode and the respective anodes, and individual controlling means for said space 125 discharges.

11. A space-discharge device comprising, in substance, a cylindrical cathode and a plurality 130 of concentric segmental grid and anode members, and a plurality of conduct-

ing vanes each extending in a radial, longitudinal plane between said segmental members.

12. A space-discharge device comprising, in substance, a cylindrical cathode and a plurality of concentric segmental grid and anode members, a plurality of conducting vanes each extending in a radial, longitudinal plane between said cylindrical members, and a conductive electrical connection between each of said vanes and one of said cylindrical members.

13. A space-discharge device comprising a cylindrical electron-emitting member, a longitudinally extending conducting vane attached thereto and extending radially therefrom, and anode means disposed thereabout.

14. A space-discharge device comprising a cylindrical electron-emitting member, a plurality of longitudinally extending conducting vanes of relatively low electron-emissivity attached to said cylindrical member and extending radially therefrom, and anode means disposed substantially in the surface of a cylinder thereabout.

15. A space-discharge device comprising a cylindrical electron-emitting member, a plurality of longitudinally extending conducting vanes of relatively low electron-emissivity attached to said cylindrical member and extending radially therefrom, a plurality of anode members spaced around said cylindrical member between the planes of said vanes, and individual space-current controlling means associated with said anode members.

16. A space-discharge device comprising an axially disposed heating member, a cylindrical cathode member surrounding the heating member and adapted to be maintained in electron-emitting condition thereby, a plurality of conducting vanes at least the greater portions of which are thermally insulated from the heated parts, each of said vanes extending in a radial, longitudinal plane, means for establishing a conductive electrical connection between said cathode member and said vanes, a plurality of anode members spaced around said cylindrical member between the planes of said vanes, and individual space-current controlling means associated with said anode members.

17. A space-discharge device, comprising an electron emitting member, a plurality of anode structures, and an auxiliary electrode at the same potential as the electron emitting member subdividing the space between said member and said structures to produce a plurality of substantially distinct space-current discharges.

18. A space-discharge device comprising an electron emitting member, a plurality of anode structures, and one or more conducting shields subdividing the space between said electron-emitting member and said anode structures into distinct compartments individual to each anode structure.

In testimony whereof, I have hereunto subscribed my name this 8th day of March, 1923.

FREDERICK S. McCULLOUGH.
